UNITED STATES PATENT OFFICE.

PIETRO CROSTI, OF MILAN, ITALY.

STEAM-LOCOMOTIVE.

1,277,554.

Specification of Letters Patent. Patented Sept. 3, 1918.

Application filed October 20, 1913. Serial No. 796,254.

To all whom it may concern:

Be it known that I, PIETRO CROSTI, subject of the King of Italy, resident of Milan, in the Kingdom of Italy, No. 12 Via Pietro 5 Verri, have invented new and useful Improvements in Steam-Locomotives, of which the following is a specification.

This invention relates to steam locomotives, and it proposes certain hereinafter 10 described improvements in the construction of the boiler used in connection with the same, or forming parts thereof.

According to the present invention, the boiler consists of a plurality of cylinders, 15 rigidly connected to a common fire-box, the construction of the parts being such as to obtain the following advantages:—increased production of steam without exceedingly increasing either the diameters of the boiler 20 cylinders, or the length of the boiler tubes; easy access to the interior of the boiler; increased area of directly-heated surface; great height of the water level over the top 25 of the fire-box; and the ability to utilize gas-passages of large section; to employ two or more stokers or mechanical stoking devices, and to maintain the center of gravity just above the geometrical axis of the locomotive.

30 An embodiment of the invention is shown in the accompanying drawing, in which: Figure 1 is a general side elevation of the locomotive.

Fig. 2 a plan of same.

35 Fig. 3 a cross section.

Fig. 4 a front view.

Fig. 5 a diagrammatic longitudinal section of the improved boiler suited to such a locomotive.

40 Fig. 6 a cross section on line A—A (Fig. 5).

Fig. 7 a cross section on line B—B of the same figure.

Fig. 8 a longitudinal section of the ash-45 pit.

Fig. 9 a plan of same.

The drawings are quite diagrammatic as the structural details can vary in each case according to special requirements.

50 Propulsion is obtained by means of two equal groups of steam cylinders 1 situated respectively at the ends of the locomotive

and shown in the drawings as consisting, each, of a pair of cylinders: the axle cranks 2 are positioned one with respect to the other in such a manner as to neutralize the effect of the alternate action of the two groups.

The boiler is symmetrical and is shown in Fig. 1 in dotted lines and in Fig. 2 in full 60 lines. It consists, in the present instance, of two cylindrical metallic shells 16, which are horizontal and symmetrical with respect to the geometrical axis of the boiler, in each of which is a bundle of tubes 15, fixed at 65 their ends to the corresponding tube-plates 3 and 4; the plates 3 are adjacent to the funnels, while the plates 4 constitute the two end walls of a specially-constructed fire-box 6, common to both cylinders 16, 70 which latter are connected at their ends to the end walls of the enlarged central portion or drum 5 of the boiler, said drum containing the fire-box 6.

This fire-box may have either a plain top 75 plate 7 without any addition of other directly heated surface, or it may have secured to it, as shown in Figs. 5 and 6, the upper ends of one or more descending bundles of free expanding water tubes 8 fixed at their 80 lower ends to one or more semi-cylindrical drums 9 which can be reached through the man-hole tubes 8'.

The steam chamber 11 above the fire-box, can be reached, in the latter instance, 85 through a man-hole or holes made in the top wall 12 of the drum 5.

In this way the water tubes 8 and the drum or drums 9 are situated within the fire-box 6, which latter is provided with 90 fire-doors 17, while the position of the water and steam conduits, and the level of the water 10 and the steam-chamber 11 depend upon the shape and size of the cylinders 16 and drum 5, forming the outer walls of the 95 boiler upon which may, if desired, be mounted the drums 13.

To reduce the displacements of the liquid mass existing in the boiler the perforated diaphragm 14 is resorted to.

100 At the base of the fire-box 6 is hung the ash-pit having also a symmetrical shape, with respect to the geometrical axis of the locomotive.

This ash-pit Figs. 8 and 9 is divided into several adjacent hopper or similarly shaped parts, (two hoppers 18 and 19 being shown in the drawing) having inclined end walls 5 20, 21, 22, 23. These walls are formed with air inlet passages 24—25—26—27, provided with closing doors 28—29—30—31 located above the bottom of the ash-pit and conveniently actuated by means of rods and 10 levers 32 by the men in charge of the locomotive.

In the sides of the hoppers 18—19 draft openings 33 may be provided and fitted with dampers 34 actuated by any convenient 15 means, which allow their total or partial opening or shutting, as well as their change of direction according to the direction in which the locomotive is running. The bottom walls of the hoppers are provided with 20 doors 35 which close the openings 36 for the discharge of ashes and the like; these doors can open automatically on account of the weight of the ashes which fall on them; in 25 this case they will be provided with a convenient counter-weight or spring, or they may be actuated by the men on the engine by means of the connecting rods 37.

The symmetrical construction of the boiler as well as the symmetrical disposition both 30 of the parts constituting the engine proper as well as of the water-tanks and fuel bunkers, require that this locomotive, whether stopping or running, may be easily reached and worked at any point by the 35 attendants in order to permit it to be driven in both directions. Therefore, with the view of obtaining the direct communication of the locomotive with the train, to control both the boiler and the gears, both when stopping 40 and running, to allow the driver to change his place to drive the locomotive according to the way it goes, standing at the farther end of the locomotive which is at the head of the train, and, lastly, in order to prevent the 45 isolation of the engine-driver from the staff both of the engine and of the train, there is provided an uninterrupted corridor or passage 38, (Fig. 2), which extends entirely around the boiler and is inclosed by the 50 outer wall 39 of the locomotive.

Along this wall 39 are positioned symmetrically and with respect to the geometrical axis of the locomotive the boxes 40 for the fuel (four in the drawing), the end 55 doors 41 to communicate with the tender and with the carriages, and the two hand wheels 42, also at the ends, which are interconnected and each of which controls the locomotive as a whole.

Upon the floor and upon the inner sides 60 of the corridor are the doors 43 for inspecting the gears situated beneath the corridor.

Doors 44 and windows 45 situated at suitable points in the wall 39 complete the 65 structure.

In the case of a tank-locomotive the water tanks can also be distributed symmetrically around the engine with respect to its geometrical axis and communicating with each other.

Having now described my invention and how the same is to be carried out, what I claim as my invention, is:

1. A locomotive boiler, comprising a pair of endwise alining, horizontal cylindrical shells; a drum arranged between said shells and to which the inner ends thereof are rigidly secured; a fire-box, common to both shells, arranged within said drum and having its top plate spaced below the top plate 80 of said drum to provide a steam and water chamber therebetween; a bundle of vertical water tubes arranged wholly within said fire-box, said tubes secured at their upper ends to the top plate of said fire-box, and opening at said ends through said top plate into said chamber; a water containing drum arranged within said fire-box to be heated directly by the fire, and to which the lower ends of said tubes are secured, to convey 85 water thereinto from said chamber; and a bundle of horizontal tubes arranged within each shell and secured at their inner ends to the adjacent end wall of said fire-box.

2. A locomotive boiler, comprising a pair 95 of endwise alining, horizontal cylindrical shells; a drum arranged between said shells and to which the inner ends thereof are rigidly secured; a fire-box, common to both shells, arranged within said drum and having its top plate spaced below the top plate 100 of said drum to provide a steam and water chamber therebetween; a bundle of vertical water tubes arranged wholly within said fire-box, said tubes secured at their upper ends to the top plate of said fire-box, and opening at said ends through said top plate into said chamber; a drum arranged within 105 said fire-box and to which the lower ends of said tubes are secured; a drum mounted above each shell and parallel therewith, said drums communicating intermediate their ends with said shells and opening at their inner ends into said chamber, so as to constitute extensions of the latter; a vertical, 110 perforated diaphragm disposed centrally within said chamber; and a bundle of horizontal tubes arranged within each shell and secured at their inner ends to the adjacent 115 end wall of said fire-box.

3. A locomotive boiler, comprising a pair 120 of endwise-alining, horizontal cylindrical shells; a drum arranged between said shells and to which the inner ends thereof are rigidly secured; a fire-box, common to both 125 shells, arranged within said drum and having its top plate spaced below the top plate of said drum to provide a steam and water chamber therebetween; a drum mounted above and parallel with each shell and com- 130

5
municating intermediate its ends with the adjacent shell and opening at its inner end into said chamber, so as to constitute an extension of the latter; and a bundle of horizontal tubes arranged within each shell and secured at their inner ends to the adjacent end wall of said fire-box.

In testimony whereof I hereunto affix my signature in the presence of two witnesses.

PIETRO CROSTI.
